UNITED STATES PATENT OFFICE.

THOMAS E. PRAY, OF CHICAGO, ILLINOIS, ASSIGNOR TO GOODMAN MANUFACTURING COMPANY, OF CHICAGO, ILLINOIS, A CORPORATION OF ILLINOIS.

MINING MACHINE.

Application filed December 26, 1924. Serial No. 758,036.

This invention relates to improvements in mining machines and more particularly to mining machines of the low vein type, so called because of their ability to be operated in rooms having relatively low ceilings and to cut close to the floor.

It is to be understood that machines of the type herein disclosed are designed to be advanced transversely of the mine wall and from right to left, with the body or main portion of the machine standing substantially at right angles to the wall face. The cutter bar extends from the forward end of the machine, and into the wall or vein being cut, the cutter chain carried thereby, carrying the cuttings outwardly from the kerf and into a space in the forward part of the machine body.

To clear the cuttings as they are removed is the purpose of the device embodying the present invention, the same acting in conjunction with the cutter chain, to deliver the cuttings clear of the machine as the cutting progresses, as will now be described in connection with the accompanying drawings, in which:

Figure 1 is a top plan view of the machine with the top wall of the frame housing reversed;

Figure 2 is a view in side elevation of the machine with the side wall of the frame housing broken away; and

Figure 3 is a cross sectional view taken on line 3—3 of Figure 2.

The machine embodying the invention consists generally of a frame housing 1, in the form of a rectangular casing, elongated lengthwise of the machine and relatively reduced in height. Just behind the housing 1 is the motor housing 2, a separate casing, containing the motor 3. The frame and motor housings are joined end to end, both being bolted to a bottom plate or pan 4, on which the machine slides along the mine floor. As clearly shown in Figure 3, the housings are elevated above the bottom plate, there being a space between the bottom walls 1^a and 2^a of the housings and the plate, varying from about a quarter of the total height of the machine throughout the greater part of the bottom area, to a little more than half throughout the forward end of the machine and adjacent the path of the cutter chain 5, which is carried on the cutter bar 6, projecting from beneath the

forward end of the machine a distance of 8 or 10 feet. The cutter chain is endless and consists of links, carrying cutting tools 5^a. The forward end of the cutter bar carries an idle sprocket (not shown in detail) on 60 which the chain travels in changing direction. Immediately beyond the rear end of the cutter bar and centrally of the frame housing is another sprocket 7, likewise carrying the cutter chain, this sprocket being 65 driven by mechanism operatively connected with the motor 3, as follows:

Extending lengthwise of the frame housing is a main drive shaft 8, supported at its ends in bearings 9, 9, near each end of the housing. The armature shaft of the motor is extended through the adjacent end walls of the housings, into the frame housing, and carries at its end a spur gear 10. The main drive shaft 8 carries a spur gear which 70 meshes with the spur gear 11, said shaft being offset above the axis of the armature shaft as shown in Figure 3.

Loosely mounted in the main shaft 8 and at its forward end is a sleeve 12, having an integral bevel pinion 13, at its forward end and clutch teeth 14 at its rear end. The pinion 13 meshes with and drives a bevel gear 15 keyed to the upper end of a vertical stub shaft 16, journaled in a sleeve bearing 17, cast integral with the bottom wall of the frame housing. At the lower end of the stub shaft 16 is the cutter chain driving sprocket 7, already mentioned. Clutch mechanism is provided for interrupting the movement of the cutter chain and consisting of a shiftable clutch sleeve 18, keyed to the main drive shaft 8, adjacent the pinion sleeve 12 said clutch sleeve having clutch teeth 18^a at its forward end adapted to engage the complementary teeth on the pinion sleeve 12.

Clutch shifting mechanism consisting of a shifting yoke 19, a rock shaft 20, and a clutch lever 21 (Figure 1) are provided for 80 shifting the clutch sleeve into and out of engagement.

In addition to driving the cutter chain, the main shaft also drives two cable drums 22, 22, mounted on a shaft 23, extending 105 transversely of the frame housing and acting to wind and pay out the cables, on which the machine depends for its movement. The drive from the main shaft to the drums 22, consists of a worm 24 keyed to the shaft at 110

its forward end, meshing with a worm wheel 25, carried on a transverse shaft 26 immediately below, said shaft carrying a spur pinion 27 at one end, meshed with an idler gear 27^a carried on a stub shaft 27^b, said idler 27^a meshing with spur gear 28 on the drive shaft 23. At the opposite end of the shaft 26 is mounted a brake drum 29 and hand operated brake band 30, but since these parts are not 10 intimately connected with the cutting action of the machine they need not be described in greater detail.

Referring now to the mechanism embodying the improvement of the present invention, the same consists of an auxiliary chain conveyor 31, located for the most part in the space between the motor housing 2 and the bottom plate 4. This chain conveyor is likewise endless and extends generally from the 20 rear end of the cutter chain to the rear end of the machine, its forward end being offset slightly from the center of the machine and toward the left or following side thereof, and extending rearwardly at an angle of 25 substantially 30° to the longitudinal axis of the machine. In this connection it is to be observed that openings from the space between the underside of the housings for the motor and feed and cutter chain driving 30 gearing, and the bottom plate 4, are provided along the following side of the machine immediately adjacent the forward end of the conveyor chain as well as along the rear end of the machine. The conveyor chain differs 35 from the cutter chain in that the links thereof are equipped with vertically set blades 32, which extend outwardly and at right angles to the chain.

The rear end of the conveyor chain turns 40 on an idler sprocket 33 (Figure 3) journaled on a vertical stub shaft 34 mounted in a bearing 35, supported upon the bottom plate 4. The forward end of the conveyor chain is carried on a driven sprocket 36, keyed to 45 a vertical shaft 37, journaled in a bearing sleeve 38, extending through the bottom wall 1^a of the frame housing from the interior thereof. Within a housing 39 at the upper end of the bearing 38 is a worm wheel 40, 50 which meshes with a worm 41, keyed to a short stub shaft 42, extending parallel with the main drive shaft 8. This stub shaft carries a spur pinion 43 which meshes with the drive pinion 10 on the armature shaft of the 55 motor. As indicated by the arrows in Figure 1, both the clutch chain and the conveyor chain travel in a counter-clockwise direction, the former carrying the cuttings rearwardly 60 into the space immediately surrounding the driving sprocket 7 thereof, where they are thrown off and outwardly as the cutter tools change direction. At this point 65 the blades of the conveyor chain pick up the cuttings and carry them on to the opening at the rear end of the machine

through which opening they are discharged.

It is to be observed that the general movement of the cuttings when they reach the rear end of the cutter chain is generally transversely of the conveyor chain, so that 70 there is practically a continuous movement of the material in a rearward direction, that is from the front to the rear end of the machine. It is to be noted also that any cuttings that are not freed from the conveyor chain at the 75 rear of the machine, but are carried forwardly on the return lead, would be thrown off when reaching the forward end and discharged through the side opening, and from the following side of the machine.

The advantage of this construction is the provision of positive conveying means for disposing of the cuttings, a problem that is always present in the operation of mining machines, since the cuttings are ordinarily 85 worth salvaging, and therefore it is desirable that they be discharged at a point where the material can be handled readily by the workers, and at the same time, not interfere with the movement or operation of the machine.

While I have shown and described one embodiment of my invention, it will be understood that the construction and arrangement of the various parts may be altered without departing from the spirit and scope thereof. Furthermore, I do not wish to be construed as limiting myself to the particular construction illustrated, excepting as it may be limited in the appended claims.

I claim as my invention:

1. A mining machine comprising a frame slideable on its bottom along a mine floor and having flexible draft means, a chain carrying cutter bar projecting forwardly of said frame, a motor rearwardly of said frame and cutter bar, an underframe vertically spacing said motor from the ground, and an endless conveyor extending from a point adjacent the rearward portion of said cutter chain rearwardly beneath said motor for conveying the cuttings discharged from said cutter chain from the rear end of said machine.

2. A mining machine comprising a frame slideable on its bottom along a mine floor and having flexible draft means, a chain carrying cutter bar projecting forwardly of said frame, a motor rearwardly of said frame and cutter bar, an underframe vertically spacing said motor from the ground and opening to the rear and following side of the machine, and an endless conveyor extending from a point adjacent the rearward portion of said cutter chain rearwardly beneath said motor for conveying the cuttings discharged from said cutter chain from the rear end of said machine.

3. In a mining machine, a frame slideable on its bottom along a mine floor and having flexible draft means, a motor disposed

- at the rear end of said frame, a chain carrying cutter bar projecting forwardly from said frame and disposed in front of said motor, said frame forming a channel for cuttings at opposite sides occupying substantially the same vertical dimensions 25
- 5 cuttings at opposite sides occupying substantially the same vertical dimensions as said cutter bar in front of said motor and an underframe spacing said motor vertically from the ground and forming a discharge passage of less vertical dimensions than the cuttings channel, an 30
- 10 endless conveyor extending from said cuttings channel at a point forward of said motor and rearwardly through said discharge passage underneath said motor for clearing the cuttings at the rear of said machine, and means located forwardly of said 35
- 15 motor and driven from the latter for actuating said conveyor.
4. In a mining machine, a frame slideable on its bottom along a mine floor and having flexible draft means, a motor disposed at the rear end of said frame, a chain carrying cutter bar projecting forwardly from
- 20
- 25
- 30
- 35
- 40

Signed at Chicago, in the county of Cook and State of Illinois, this 24th day of December, A. D. 1924.
